UNITED STATES PATENT OFFICE.

ERNEST A. MENKING, OF PITTSBURG, PENNSYLVANIA.

SUCTION-VALVE FOR COMPRESSORS.

SPECIFICATION forming part of Letters Patent No. 735,549, dated August 4, 1903.

Application filed March 6, 1903. Serial No. 146,500. (No model.)

To all whom it may concern:

Be it known that I, ERNEST A. MENKING, a citizen of the United States, and a resident of Pittsburgh, in the county of Allegheny and State of Pennsylvania, have invented a new and Improved Suction-Valve for Compressors, of which the following is a full, clear, and exact description.

This invention relates to valves; and it consists, substantially, in the improvements hereinafter particularly described.

The invention has reference more especially to spring-controlled puppet or suction valves, such, for instance, as are employed in connection with cylinders of air, gas, or other compressors or the like; and the principal object of the invention is to provide a valve structure of this character which is effective in operation and which may also be regulated with facility, whereby no hammering or noises are produced by the valve when the same is in use.

A further object is to provide a spring-controlled puppet or suction valve which is constructed of few parts, which are easily and quickly assembled or organized for operation, and also to provide means whereby access may be readily had to the valve and its accessories either for the purposes of repair or other attention thereto.

A further object of the invention is to provide simplified and effective yieldable devices for normally maintaining the valve upon its seat and also to provide a puppet or suction valve structure for the purposes named which possesses certain advantages over many other structures of a like character heretofore devised.

A still further object is to overcome several objections common to many like structures at present in use for similar purposes and also to provide a valve structure of this general character having the capacity for long and continued service, besides being comparatively cheap to manufacture as well as readily adapted to operative position within the compressor or other cylinder without liability to leakage or other defects.

The above and additional advantages are attained by means substantially such as are illustrated in the accompanying drawings, in which—

Figure 1 is a part longitudinal sectional elevation of a compression-cylinder, showing my improved puppet or suction valve structure as employed in connection with ports of said cylinder. Fig. 2 is an enlarged vertical part-sectional elevation in detail of my improved puppet or suction valve structure, said view indicating more clearly the construction and organization of the several elements or parts constituting the structure. Fig. 3 is an enlarged view in side elevation of the cage or housing for the valve and its several adjuncts, the separable parts or sections constituting the said cage or housing being shown in segregated relation. Fig. 4 is a top or plan view of the construction shown in Fig. 2, with the top plate of the compression-cylinder removed. Fig. 5 is a horizontal sectional plan view taken on the line 5 5 in Fig. 2, said view being minus the controlling-spring for the valve and showing the pocket or seat for the lower end of the said spring; and Fig. 6 is an enlarged side view of the valve itself, together with its stem and head thereon.

Before proceeding with a more detailed description it may be stated that my improved puppet or suction valve structure for compressors and the like comprises a valve and a seat therefor, each of a certain preferred construction, combined with a cage or housing for the valve, together with the accessories and controlling devices for the latter, said cage or housing being of special construction or embodiment, and the said accessories and controlling devices being also specially constructed and organized, as will hereinafter more fully appear.

It may be stated that while I have herein represented my improvements in a certain preferred embodiment or organization I am not limited to the precise details thereof in practice, since immaterial changes may be resorted to coming within the scope of my invention.

Specific reference being had to the several parts of the drawings by the designating characters marked thereon, 1 represents the outer wall or structure of an air, gas, or other compressor formed with the usual chamber 2, in which works or reciprocates a piston 3, having the usual operating-rod 4, connected to any suitable motive power. The accompany-

ing illustration, Fig. 1, is simply employed for the purpose of showing the adaptation and operation of my improved valve structure. Formed or otherwise provided in the 5 upper part of the casing of the compressor are suitable ports 5, connected by a passage 6, one of my improved valve structures being located above each of said ports and held or supported in position in a suitable 10 opening 7, formed in the upper wall 8 of the compressor, said openings each being provided with a removable cover or top plate 9 for preventing dirt and other objectionable substances from gaining access to the interior 15 of the valve structure, said covers or top plates also serving to retain the structure in rigid position within the support therefor, substantially as will be more fully explained hereinafter. The compressor itself is with- 20 out other special features of construction, it being observed that a pipe 10 leads upwardly from the passage 6 and which may be connected to any suitable source of supply of air, gas, or similar fluid.

25 My improved valve structure comprises a ring 11, (see Fig. 2,) located at the lower part thereof, as shown, the said ring being snugly fitted within the sides, forming or constituting, as may be said, one of the ports 5 30 already referred to. The vertical circular portion 12 of the said ring 11 is screw-threaded internally at 13 and is formed internally with an annular ledge or shoulder 14, while the lower edge of the conical portion of the ring is 35 preferably beveled or flared outwardly at 15 to constitute or form a seat for the disk or valve 16, which is beveled at 17 in correspondence therewith, the said valve being formed or provided centrally of the upper surface there- 40 of with an upwardly-projecting stem 18, said stem being provided at the upper end thereof with an integral cap or head 19, as shown. Surrounding or inclosing the said valve-stem 18 is a cage or housing 20, which, as indicated 45 in Figs. 2 and 3, is practically skeleton-like in construction, and is constituted, preferably, of two separable sections 21, 21, each being substantially semicylindrical in plan view and each of said sections being provided at the 50 upper and lower ends thereof, respectively, with semicylindrical extensions 22 and 23, said extensions being so constructed on their external surfaces as to present continuous screw-threads 24 and 25 when the two said 55 sections 21 of the cage or housing are properly assembled in place. Each of the said sections 21 is also provided at a suitable distance from the upper and lower parts thereof, respectively, with semicylindrical projections 60 26 and 27, which when the cage-sections are united present continuous ring-like portions surrounding the said cage or housing. The inner adjacent surfaces of the meeting portions 28 and 29 of the said sections 21 of the 65 cage or housing are provided, respectively, with a recess 30 and a projection 31, the one receiving the other when the two cage-sections

are properly united, and said sections being thereby held in proper position relatively to each other without liability to displacement 70 thereof. Each of the cage-sections 21 is also provided interiorly with a semicylindrical support 32, each having in the upper surface thereof a semicylindrical recess 33, and when the said cage-sections are united in proper 75 relationship to each other the said supports 32 are thereby brought together, and the sides of the said recesses unite in forming a continuous annular pocket or seat for the lower end of a coil-spring 34, (see Fig. 2,) through 80 the medium of which the valve is controlled or normally maintained tightly upon its seat. As will be observed, each of the said sections 21 of the cage or housing for my improved valve structure is also provided interiorly 85 with a semicylindrical vertical extension 35, the two said extensions uniting in the formation of a vertical guide for the accommodation and working of the said valve-stem 18, as shown. The said spring 34 is of suitable 90 power or strength and the upper coil thereof is received in an annular seat or bearing 36, formed in the under side of a ring 37, which is slipped in place over the head 19 of the valve-stem, it being observed that the inner 95 diameter of said ring is considerably in excess of the external diameter of the said valve- stem. In order to maintain the said ring 37 in place as well as to obtain the desired effects of the expansive force of the spring, I 100 employ a split ring 38, or rather a ring made in two sections which are provided with pendant portions 39, fitting snugly in the annular space formed intermediate of the adjacent 105 surface portions of the valve-stem and the said ring 37. The pressure of the spring 34 forces both the ring 37 and the split or divided ring 38 upwardly, so that a compact relationship exists between the same and the valve- 110 head, and it will be apparent that when the parts or elements are united, as herein explained, the most effective results are derived therefrom.

Fitted to the upper extensions 22 of the sections of the cage or housing of my improved 115 valve structure is a ring 40, which is screw-threaded internally at 41 to fit the threads 24 of the said extensions, said ring being also formed internally with an annular shoulder 42, which rests upon the upper edge of the 120 said extensions.

In assembling or organizing the several elements or parts of my improved valve structure it may be stated that the valve-stem 18 of the valve is inserted upwardly through the 125 ring 11 from beneath, so as to cause the valve to be properly located upon the seat 15 therefor, whereupon the two halves or sections 21 21 of the cage or housing 20 are brought together, so that the threads on the extensions 130 22 and 23 thereof are brought into continuity and also so that the internal vertical extensions 35 thereof are brought in proper position on opposite sides of the valve-stem, by

which the latter will be properly guided in the movements of the valve. The said ring 11 is then screwed upon the united extensions 23 of the said sections 21, as indicated in Fig. 2, whereupon the spring 34 is slipped down over the inner extensions or valve-guides 35, so as to have the lower coil thereof properly located in the annular pocket or seat therefor formed in the upper surface of the 10 semicylindrical supports 32. After this assemblage of the parts or elements specified the said ring 37 is slipped over the valve-head, so as to rest upon the upper coil of the spring 34 in the manner already explained, and then 15 the split or divided ring 38 is also applied to the valve-stem beneath the head 19 thereof. From this description it is believed that the construction and organization of my improved structure will be fully understood, as well 20 as the operation thereof, it being stated, however, that subsequent to the application or fitting in place of the said ring 38 the said ring 40 is screwed upon the united extensions 22 of the sections 21 of the cage or housing, 25 after which the cover or top plate 9 may be secured in place, as herein shown and for the purpose hereinbefore mentioned.

It is of course apparent that my improved valve structure may be mounted in position 30 in other ways than that herein shown and described and that the same may also be altered in immaterial respects, according to the exigencies or requirements demanded by the

particular conditions under which it may be desired to employ the structure.

Having thus described my invention, I claim as new and desire to secure by Letters Patent—

A valve structure for compressors and the like, comprising an internally-threaded ring 40 having a valve-seat, a valve having a stem provided with a head, an inclosing cage constructed of substantially semicylindrical sections, each formed externally with semicylindrical projections, which are flush with said ring, and each also having a semicylindrical internal extension, the two latter uniting to form a guide for the stem, a spring surrounding the guide, said guide having recessed portions constituting a bearing for one end of 50 the spring, and a bearing for the other end of said spring, adapted to be applied over said head, said cage-sections having another internally-threaded ring surrounding the same adjacent the head, and each section having 55 a semicylindrical threaded extension at each end to receive said first-named ring and the ring last named.

In testimony whereof I have signed my name to this specification in the presence of 60 two subscribing witnesses.

ERNEST A. MENKING.
